United States Patent Office.

CHARLES F. CREHORE, OF NEWTON LOWER FALLS, MASSACHUSETTS.

Letters Patent No. 74,996, dated March 3, 1868.

IMPROVED PROCESS OF TREATING PAPER FOR VARIOUS PURPOSES.

The Schedule referred to in these Letters Patent and making part of the same.

TO ALL WHOM IT MAY CONCERN:

Be it known that I, CHARLES F. CREHORE, of Newton Lower Falls, in the county of Middlesex, and State of Massachusetts, have invented a new and useful Process for Treating Different or Various Fabrications of Paper for Various Purposes; and do hereby declare the following to be a full, clear, and exact description of the same, reference being had to the specimens accompanying this specification.

The object sought in making this invention is to treat or prepare the various fabrications of paper, such as "press-papers," binder's-board, &c., in such manner as to render it comparatively hard, semi-elastic, and water-proof, and susceptible also of a highly-finished surface.

The invention consists in subjecting the paper to the action of sulphur, preferably by immersing it in a bath of boiling or melted sulphur, the temperature of which is to be regulated by the required hardness of the finished material. The action of the sulphur has the effect of rendering the paper hard, semi-elastic, and water-proof, as well as compact in body, and with a susceptibility of high finish, if desired.

Among the various instances of application of which my invention is susceptible, so far as the experiments made have proved it a success, a particular one is its use as press-paper for cloth-printers' use, as well as for those of ordinary printing, the advantages of which will at once manifest themselves to persons skilled in the craft.

For book-binders' use the requisite amount of rigidity may be obtained with great reduction in bulk and weight, and, as a consequence, in cost, as compared with the material now in use.

I claim as my invention, and desire to secure by Letters Patent of the United States—

The treatment, substantially as before described, of the different fabrication of paper, by combining the same with sulphur, or any combination with or equivalent to sulphur, for the purpose of producing the material or effects before explained.
